UNITED STATES PATENT OFFICE.

HANS H. WANDERS, OF BOSTON, MASSACHUSETTS, ASSIGNOR TO NORTHERN INDUSTRIAL CHEMICAL COMPANY, OF BOSTON, MASSACHUSETTS, A CORPORATION OF MASSACHUSETTS.

TIMER.

Application filed January 14, 1922. Serial No. 529,155.

This invention relates to timers being more particularly designed for Ford cars.

One feature of the invention relates to the manner of fixing the relatively stationary contacts within the material of the timer casing which is preferably of bakelite or similar material, by which burning of this material through arcing between the stationary and moving contacts is avoided.

Another feature relates to the construction by which dust or other foreign matter is prevented from finding its way to the interior of the casing.

A further feature relates to the construction of the moving arm and the mounting of the contact member or shoe therein.

Further features and advantageous details and combinations of parts will appear from a description of certain embodiments shown in the accompanying drawings in which—

Figure 1 is an end elevation of the timer.

Figure 2 is a section on line 2—2 of Figure 1.

Figure 3 is a section on line 3—3 of Figure 1.

Figure 4 is a fragmentary perspective of the dust guard or cap.

Figure 5 is a side elevation of a contact button before incorporation in the casing.

Figure 6 is a top plan of the button.

Figure 7 is an elevation partly in section of the button as prepared for incorporation in the casing.

Figure 8 is a fragmentary elevation of the inner face of the timer housing showing another and preferred form of stationary contact.

Figure 9 is a section on line 9—9 of Figure 8.

Figure 10 is a side elevation of the contact button of the form shown in Figures 8 and 9.

Figure 11 is an end elevation of the movable contact shoe and its mounting.

Figure 12 is a section on line 12—12 of Figure 11.

Figure 13 is a section on line 13—13 of Figure 11.

Referring to Figures 1, 2, and 3 the timer comprises a casing 1, preferably formed of a phenol condensation product such as bakelite or other similar insulating material. This casing comprises a cylindrical housing portion 2 open at one end and closed at the

other end by means of an annular portion 3 and a dome shaped end portion 4. The end of this dome shaped portion has formed therein a central depression 5 which is adapted to receive the usual arm by which the timer casing on Ford cars is held in position against the forward end of the engine casing. At 6 is shown an arm made fast to the outer face of the annular portion 3 by means of rivets as 7 embedded in the material of the casing and headed over the outer face of the arm. This arm terminates in a rounded boss 8 having a central perforation 9 therethrough to which is attached the usual control arm by which the timer casing may be oscillated to vary the timing of the ignition. The portion 3 of the casing carries in circular series relatively stationary contacts which are preferably composed of metallic buttons such as 10 molded through the material of the casing and having on their outer ends threaded extensions 11 for the reception of nuts by which the wires leading to the spark plugs may be attached. These wires are commonly coated with insulating material differently colored for the various cylinders and if desired the casing may have molded therein corresponding legends identifying the wires to be fastened to each button.

It is found in practice that the arc produced by the making and breaking of contact between the usual rotary contact member or shoe and the relatively stationary contact buttons is liable to burn the material of the casing, thus causing injury thereto. For the purpose of eliminating this difficulty certain constructions which will now be described have been designed. One method of overcoming this difficulty is disclosed in Figures 1 to 3 and 5 to 7 inclusive. In this method the annular portion 3 is originally molded somewhat thicker than is desired for the finished casing, this thickness being indicated on its inner side by the dotted line in Figure 3. The buttons are made as shown in Figure 5, each having an annular knurled portion 15 to permit the material molded thereabout to find a firm hold. Adjacent this knurled portion is an outwardly extending flange 16 defining with a similar flange 17 an annular recessed portion 18. The recessed portion 18 is filled with rubber or other suitable gum 19 and

is vulcanized substantially flush with the peripheries of the flanges 16 and 17. This construction is shown in Figure 7. The button so prepared is then molded in the 5 casing in the position shown in Figure 3 and the casing is then placed in a suitable machine and the inner face of the portion 3 together with the flanged end 17 of the button is removed, this causing the inner end 10 face of the button to be of the diameter of the portion 18 and to be flush with the inner face of the casing, the casing being recessed about the inner face of the button and a ring of the rubber or vulcanizable gum being seated in the recess and so interposed between their exposed surfaces. Any arcing which takes place between the movable shoe and contacts therefore takes place over 15 the gum portion and is not liable to burn 20 the material of the casing itself.

Another and preferred construction, in which the recesses about the contact faces of the buttons are not filled with gum or other substance, is shown in Figures 8, 9 25 and 10. In this form each button is provided with a circular portion having a knurled periphery at 20 between portions 21 and 22 of reduced diameter. The button so made is molded through the annular wall 3, 30 the inner end of the reduced portion 22 being flush with the inner wall of the casing. Molded or cut in the inner face of this casing is a pair of segmental slots 23 which serve to separate the contact face of the button 35 from the inner face of the casing at diametrically opposite points and in line with the movement of the contact shoe. Any arcing which takes place in this construction takes 40 place at the air gap formed by the slots 23 and therefore does not burn the casing.

The preferred form of contact shoe which is designed to serially contact the inner faces of the buttons is shown in Figures 11, 12 and 13. A collar 30 is designed to be placed 45 over the end of the timer shaft which is shown at dotted lines in Figure 2, this collar being held for rotation with the shaft by any suitable means (not shown). The inner end of this collar has an enlarged flange portion 31 against the outer face of which is 50 designed to be made fast a contact shoe carrying arm 32. This arm is preferably composed of sheet material having a perforation 33 therethrough through which the 55 small portion of the sleeve 30 may pass. Suitable fastening means such as rivets 34 may then be passed through the arm and the flange 31 parallel to the axis of the sleeve for retaining the arm in position relative 60 thereto. The outer end of this arm has an opening 35 therethrough which is designed to receive a contact shoe 36 which is provided at one end with a head 37 of larger size than the opening 35 which holds the 65 shoe from passing completely through the

opening. This shoe is positioned to contact serially on the inner faces of the buttons as it is rotated by rotation of the shaft 31. It is held against these buttons or the inner face of the annular portion 3 by resilient 70 means. This means as herein shown comprises a double spring member 38 which is coiled at 39 about a pintle 40 and has an arm 41 extending over and into engagement with a groove 42 in the head 37 and the rear 75 ends of which at 43 are held in fixed position. For the purpose of supporting the pintle pin 40 a pair of ears 44 may be struck upwardly from the material of the arm, these ears being perforated for the reception 80 of the pintle. For the purpose of holding the spring ends 43 in fixed position the material of the arm adjacent the collar or flange portion 31 may be bent to form a pair of ridges 45 (see Figure 13) to provide between 85 the arm and the flange 31 a pair of grooves for the reception of the ends 43. In order to further stiffen the arm its opposite side edges may be turned up to form stiffening flanges 46 and one of these flanges may be 90 cut away as at 47 to form an opening through which the pintle 40 may be inserted or removed. This pintle as shown comprises a cotter pin having a looped end 48 of usual form which is readily engageable for insertion or removal thereof.

In order to provide a more reliable electrical connection between the shoe and the arm than is afforded by contact of the shoe with the sides of the opening 35, and through 100 the spring 38, a flexible conductor 49 may be attached at one end to the shoe and at its other end to the arm, as herein shown, the connection to the arm being made through one of the flanges 46. This connection is of 105 such length that the motion of the shoe through the opening 35 is not restricted. The sleeve 30 together with the shoe is contained within the casing 1 being slipped over the end of the timer shaft before the casing 110 is placed in position.

In order to prevent the entry of dust or other foreign matter into the casing it is preferable to employ a dust guard or plate shown at 50 in Figures 2, 3 and 4. This 115 plate has a central perforation 51 of sufficient diameter to permit the timer shaft 31 to pass freely therethrough. This plate is dished surrounding the perforation 51 as shown at 52, and the outer marginal portion 120 thereof is flanged over as shown at 53. This flanged portion fits closely in a counterbored portion 54 at the open end of the casing 1 so that the casing is free to be rocked thereabout, and seated in the dished portion 52 is 125 a suitable washer 55 preferably of felt or similar material which forms a packing between the timer shaft and the perforation 51. This packing bears against the outer end of the engine casing shown in dotted lines at 130

56 (see Figures 2 and 3) and the annular portion 57 immediately within the flange 53 also rests against the engine casing. By this means the entry of foreign matter between 5 the timer casing and the engine casing and into the timer is prevented.

Having thus described certain embodiments of this invention it should be evident to those skilled in the art that many changes 10 and modifications might be made therein without departing from its spirit or scope as defined by the appended claims.

I claim:—

1. The method of fastening a contact button in a timer casing which comprises forming the button with a circumferential groove, filling said groove with a vulcanizable gum, and molding the button in the casing.

2. The method of making a timer which comprises forming a plurality of contact buttons with circumferential grooves therein, molding rubber in said grooves, and molding the buttons with the rubber thereon in the walls of a timer casing.

3. The method of making a timer which comprises forming each of a plurality of contact buttons with a circumferential groove therein forming an outwardly extending flange at one end, molding rubber in said grooves, molding the buttons with the rubber thereon in the wall of a timer casing, and turning off the inner face of said casing and the inner ends of said buttons to remove said flanges at the ends of said buttons and the inner surface of said casing.

4. A timer comprising a casing of moldable material, a plurality of contact buttons extending through the wall of said casing, and a rubber ring interposed between said buttons and said wall on one face thereof.

5. In a timer, a flanged rotary timing shaft, an arm of sheet material made fast to said flange and having an opening

through which said shaft passes and an opening near its free end, lugs struck from the material of said arm, a shoe having a head larger than the opening in the free 50 end of said arm loosely positioned in said opening, a pintle carried by said lugs, and a spring coiled about said pintle and bearing at opposite ends respectively on the head of said shoe and between the shaft flange 55 and said arm.

6. In a timer, a flanged rotary timing shaft, an arm of sheet material made fast to said flange and having an opening through which said shaft passes, and an 60 opening near its free end, stiffening flanges at opposite sides of said arm, lugs struck from the material of said arm between said stiffening flanges, a shoe having a head larger than the opening in the free end of 65 said arm loosely positioned in said opening, a pintle carried by said lugs, and a spring coiled about said pintle and bearing at opposite ends, respectively, on the head of said shoe and between the shaft 70 flange and said arm.

7. In a timer, a flanged rotary timing shaft, an arm of sheet material made fast to said flange and having an opening through which said shaft passes, and an 75 opening near its free end, stiffening flanges at opposite sides of said arm, lugs struck from the material of said arm between said stiffening flanges, a shoe having a head larger than the opening in the free end of 80 said arm loosely positioned in said opening, a pintle carried by said lugs, and a spring coiled about said pintle and bearing at opposite ends, respectively, on the head of said shoe and between the shaft 85 flange and said arm, one of said stiffening flanges having an opening through which said pintle may be inserted or removed.

In testimony whereof I have affixed my signature.

HANS H. WANDERS.
